UNITED STATES PATENT OFFICE.

ALEX MONICH, OF NEW BRITAIN, CONNECTICUT.

CURTAIN-SUPPORTER.

1,072,144.

Specification of Letters Patent.

Patented Sept. 2, 1913.

Application filed December 27, 1912. Serial No. 738,797.

To all whom it may concern:

Be it known that I, ALEX MONICH, a citizen of Austria, residing at New Britain, in the county of Hartford and State of Connecticut, have invented certain new and useful Improvements in Curtain-Supporters, of which the following is a specification.

My invention relates to improvements in curtain supporters and the object of my improvement is to produce a curtain supporter that has simple and reliable means for supporting a curtain pole and which in some cases happens to be suitable for use with certain shade roller holders or supporters of well known form such as are shown and will be described.

In the accompanying drawing:—Figure 1 is a front elevation of a pair of my curtain and shade roller holders, a shade roller and part of a curtain pole supported thereby and part of the casing for a window. Fig. 2 is a similar view on an enlarged scale of one of the shade roller holders shown in Fig. 1. Fig. 3 is a plan view of the same. Fig. 4 is an end elevation of the same. Fig. 5 is a corresponding view of the other holder shown in Fig. 1. Fig. 6 is a sectional view on a further enlarged scale on the line $\alpha\alpha$ of Fig. 2. Fig. 7 is a sectional view on the line yy of Fig. 2. Fig. 8 is a front elevation of the moving member shown in Fig. 2. Fig. 9 is an end elevation of the same. Figs. 10 and 11 are corresponding views of the clamping bolt and nut. Fig. 12 is a sectional view on the line zz of Fig. 2.

My curtain and shade roller holder comprises a pair of mating holders respectively a left holder A and a right holder B suitable for being supported on the window casing C and provided with means for supporting a shade roller D and a curtain pole E.

The holders A and B differ only in such features as are necessary to adapt the holder A as a left holder and the holder B as a right holder, and to provide a symmetrical arrangement of the curtain and shade roller supporting members proper with reference to the window F and to provide a hole in the left holder A to hold the left end of the shade roller D and a slot 16 in the right holder B to hold the right end thereof.

The holders A and B comprise each a body member 17 on which is removably mounted a curtain pole supporting member 18 and also on which is removably and adjustably mounted a shade roller supporting

member 19. The body member 17 comprises an elongated, laterally extending base 20 that is rectangular in formation.

A guide plate 21 extends along the middle portion of the said base 20 being separated therefrom by spacing blocks 22 and held in position by rivets 23 which pass through the said guide plate 21, spacing blocks 22 and base 20.

The guide plate 21 is provided with a longitudinal slot 24 that extends from the outer end inward for the greater part of the length of the said guide plate 21. The opposed edges 25 of the slot 24 overhang the spacing members 22 in the form of flanges so as to partially close a relatively enlarged opening or slot 26 within the body member 17 between the spacing members 22.

The shade roller holder 19 is formed of sheet metal and comprises a base portion 27 suitable for resting on the guide plate 17 and flanges 25 and having a hole 28 adjacent the middle portion. An arm 29 extends forwardly from the inner end of the base portion 27 and is provided with the shade roller holding slot 16 in the case of the left member A and hole 15 in the case of the right member B.

At the outer end of the base portion 27 there is a rearwardly extending head 30 that is a loose fit for the slot 26 between the spacing members 22 and which is connected to the said outer end by a neck 31 that is a fit for the slot 24 in the guide plate 17.

A clamping screw 32 has a body portion that is receivable in the hole 28 in the base portion 27 and also in the slot 24, and which has a square head 33 that is a fit for the relatively enlarged slot 25 and is non-rotative therein. A clamping nut 34 engages with the body portion of the screw 32.

The hole 28 is appreciably separated from the head 30 so that when the said head 30 and the head 33 of the screw 32 are engaged with the slot 26 the shade roller holder 19 is held non-rotatively positioned on the guide plate 17, even when the clamping nut 34 is loosened for the purpose of changing the position of the shade roller holder 19. When the desired adjustment of spread for the shade roller holders 19 has been attained the clamping nut 34 is tightened and the holders 19 are thereby secured in the adjusted positions.

The base 20 extends appreciably above and below the guide plate 17 substantially

in the form of flanges 35, and the said flanges 35 are provided with holes 36 for supporting screws. The upper flange 35 is provided near the outer end with a hole 37 adjacent the outer edge and a hole 38 inwardly disposed relatively to the hole 37 and appreciably separated therefrom. The hole 37 is a fit for and suitable to receive a bolt or screw 39 having a nut 40 on the front end. The hole 38 is a fit for and suitable to receive the rearwardly directed tip end 41 of the supporting arm 42 of the curtain supporting member 18. The said curtain supporting member 18 is formed of a single piece of wire and which comprises the laterally directed supporting arm 42 at the inner end and having the rearwardly directed tip end 41 already mentioned at the extreme inner tip end, and at the other end of the arm 42 wire is bent upwardly to form the upwardly directed member 43. From the upper end of the upwardly directed member 43 a branch arm 44 extends forwardly and from the forward end of which the finger 45 extends upwardly suitably to engage with a hole in the curtain pole E. The members 43, 44 and 45 constitute the curtain pole supporting member proper and the arm 42 serves as the means for removably connecting the same to the flange 35. The said arm 42 is provided with a hole 55 that is a fit for the screw 39 and which is in registration with the hole 37 when the tip end 41 is engaged with the hole 38.

35 The wire of which the curtain supporting member 18 is made is preferably round and the same is flattened as shown at 46 adjacent the hole 55.

40 The screw 39 and nut 40 serve to positively hold the arm 42 to the flange 35 and

the tip end 41 engaged with the hole 38 serves as a stud or positioning pin to co-operate to position the same and prevent rotative movement of the curtain supporting member 18.

45

As described the curtain supporting member is made of a single piece of round wire and is removably secured to the body portion by a single screw, and the shade roller holder is both removably and adjustably secured to the said body portion by a single screw and both the curtain holder and shade roller holder are provided with means that co-operate with the screw elements to position the said holders particularly against being turned from the normal positions.

50

55

I claim as my invention:—

A curtain supporter comprising a body portion having a flange at the upper edge and serving as a supporting flange, the said flange being provided with a pair of holes that are separated laterally by an appreciable space, a curtain holder formed of a single piece of wire comprising a curtain supporting member at one end and a supporting arm at the other end, the free end of the said supporting arm being bent rearwardly suitably to engage with one of the said holes when the said arm is positioned in front of the said upper flange, and the said arm being provided with a hole that is in registration with the other of the said holes in the upper flange, and holding means engaged with the said holes that are in registration.
